UNITED STATES PATENT OFFICE.

JOHN W. BAKER, OF PHILADELPHIA, PENNSYLVANIA.

GAS-STOVE.

SPECIFICATION forming part of Letters Patent No. 349,779, dated September 28, 1886.

Application filed May 27, 1885. Serial No. 166,811. (No model.)

To all whom it may concern:

Be it known that I, JOHN W. BAKER, a citizen of the United States, residing in the city of Philadelphia, State of Pennsylvania, have 5 invented certain new and useful Improvements in Gas-Stoves, of which the following is a full, clear, and exact description, reference being had to the accompanying drawings, forming a part of this specification.

10 My invention relates to gas-stoves constructed with a central flue, through which the products of combustion are drawn downward to a series of upright radiating flue-tubes located between two annular drums, said central flue 15 connecting at its closed base with the lower annular drum, and being surrounded by vertical gas tubes having jets at or about the terminus of said flue, and for which I have filed application for Letters Patent on the 5th day 20 of December, 1884, being Serial No. 149,548; and my present invention consists in an improvement therein by the combination, with said central flue, of a hot-air flue located within the same, and communicating through the base 25 thereof with the open air, and extending upward to the top of the stove through the draft-chimney located above said central flue.

In the accompanying drawings, Figure 1 is a vertical section showing the relative arrangement of the several parts of my improved stove; Fig. 3, a vertical section of the gas-burning apparatus in the stove, and Fig. 2 a top view thereof.

Suitably mounted upon a frame (indicated 35 at A) is an annular ring or drum, B, connected air-tight with a like upper annular ring or drum, C, by means of a series of upright radiating flue-tubes, D D, placed between them, and within the space formed by the series of 40 tubes D D is supported a gas-burning apparatus, (shown in Figs. 2 and 3,) consisting of a central flue-chamber, F, closed at its base, except as hereinafter mentioned, and communicating air-tight with the lower drum, B, 45 by means of flue-tubes E E. A series of gas-tubes, J J, lead from a gas-chamber, L, and are arranged vertically around the central flue, F, extending up to about the top thereof. A chimney, M, preferably of funnel shape, fits 50 closely within the central circular space formed

by the shape of the upper annular ring or drum, C, and is supported thereby, extending downward from the top thereof to the region of the gas-jets, and being large enough in diameter at that point to form an annular space between 55 it and the circular series of gas-jets, so that a current of air will be induced to that point from below, and there mingle with the gas issuing from the tubes J. The central flue, F, is open at its top and closed at its base, except for a flanged 60 opening, (indicated at n,) upon which is supported an upright hot-air flue, S, open at both ends and smaller in diameter than said central flue, F, fitting air-tight in said flanged opening, and constructed, preferably, of some refractory 65 material. Gas is supplied through the tube K at the base of the stove to the gas-chamber L.

The operation is as follows: The gas which proceeds upward to the jets at the top of the 70 gas-tubes J J is there ignited, when the heat produced thereby will cause an upward current of air to the region of the jets. The draft-pipe G, leading to the chimney and connected with the upper drum, C, constitutes a draft-connection 75 for the products of combustion of the ignited gas and air, which are drawn downward through the central flue, F, to the lower drum, B, thence upward through the series of upright flue-tubes D to the upper drum, C, and 80 thence to the chimney through the pipe G. It is apparent that the central flue, F, will be thereby highly heated, and that in consequence 85 the gas in the surrounding tubes J will be heated and expanded before reaching the jets and the point of ignition. In like manner the upward current of air induced to the region of the gas-jets by means of the chimney M will be heated and expanded by contact with the surrounding hot surfaces before reaching that 90 point, and there mingle with the heated gas at the termini of the gas-tubes and be ignited therewith. Again, in like manner the hot products of combustion passing downward through 95 said central flue, F, will impart great heat to the hot-air flue S within said central flue, and will induce a current of air upward through the said hot-air flue S, from the top of which such air (which will be highly heated in its upward passage through the same) may be 100

permitted to pass into the room to be warmed, or be carried off by any suitable and usual means to other rooms or localities to be heated.

Having thus described my invention, what 5 I claim as new, and desire to secure by Letters Patent, is—

The combination constituting a gas-stove, of the annular drums B and C, and a series of upright flue-tubes, D, located between them and 10 connecting the same, a central combustion flue-chamber, F, arranged and supported between said drums and connected air-tight therewith at its base, a gas-chamber, and a series of gas-tubes, J J, surrounding said flue-chamber F, 15 and extending to the top thereof, or nearly so, a chimney, M, supported by and located at its top within the said upper annular drum, C,

and extending down to the region of the gas-jets, whereby a current of air is induced thereto, and a vertical hot-air flue, S, within said flue-chamber F, and connected therewith by a flanged opening therein at its base, and extending upward to the top of said upper annular drum, C, or nearly so, the said parts being constructed, combined, and arranged substantially 20 25 as set forth.

In testimony whereof I have hereunto affixed my signature this 29th day of April, A. D. 1885.

JOHN W. BAKER.
